ULTRA HIGH FREQUENCY AMPLIFIER

Stanley Gordon Tomlin, London W. C. 2, England, assignor to Standard Telephones and Cables Limited, London, England, a British company

Application June 2, 1942, Serial No. 445,508
In Great Britain May 10, 1941

1 Claim. (Cl. 179—171)

1

The present invention relates to ultra high frequency amplifiers and particularly though not solely to ultra high frequency amplifiers associated with circuit arrangements utilising concentric line conductors.

According to the invention an amplifier for ultra high frequencies comprises an input and an output resonant chamber arranged in alignment with each other and each containing a part of a thermionic electron discharge device comprising at least a cathode, an anode and a control grid, said cathode being electrically connected to the input chamber and the anode being electrically connected to the output chamber and said control grid being provided with an auxiliary metallic member extending outside the enclosing envelope of the discharge device and sandwiched between the walls of the two chambers to form a screen between the input and output circuits, blocking capacities being inserted in the grid-cathode path and in the grid-anode path. The blocking capacities enable direct current potentials to be applied to the respective electrodes.

In carrying the invention into practice, both said chambers may consist of a section of concentric conductor transmission line provided with an adjustable piston to tune the chambers to the frequency of operation. In an alternative arrangement either or both chambers may comprise disc resonators provided with suitable tuning arrangements, as hereinafter described. The former arrangement is particularly useful for use with concentric conductor transmission line systems.

The blocking capacities may be conveniently formed between the auxiliary metallic member of the grid and the walls of the input and output chambers, or in any other convenient part of the grid-cathode and grid-anode circuits. In this latter case the grid is directly connected to the walls of the chambers and earthed for both high frequency and direct currents. In the former case the grid is earthed as regards the high frequency currents.

The invention will be better understood from the following description taken in conjunction with the accompanying drawings, in which:

Fig. 1 shows one form of the amplifier embodying the invention; and

Fig. 2 is an explanatory diagram.

Fig. 3 shows an alternative form of output circuit.

Fig. 3A is a modification of Fig. 3.

In Fig. 1 the two chambers are indicated at 1 and 1', each comprising sections of concentric

2

conductor transmission lines having outer conductors 2, 2', respectively, and inner conductors 3, 3', respectively, with adjustable pistons 4, 4', respectively, at opposite ends as shown. The thermionic electron discharge device is shown at 5 and comprises a cathode 6, control grid 7 and anode 8 in an evacuated enclosing envelope 9. All the electrodes, as will be observed, are planar and located in parallel planes perpendicular to the axis of the chambers. The outer conductors 2, 2' are provided at the adjacent ends with flanges 10, 10' respectively, and which are parallel to each other. The control grid is provided with an annular plate member 11 integral therewith and preferably of copper. This annular plate member 11 is located between the two flanges 10, 10', so as to form therewith capacitive couplings. The central conductor 3 is shown as a hollow conductor serving as one lead for the cathode heater, the other lead being a conductor within 3 as shown.

The input feed circuit is shown as a concentric line 12, 13, the outer conductor 12 of which is slidably connected to the outer conductor or wall 25 of chamber 2 and the inner conductor 13 thereof is slidably connected to the inner conductor or wall of chamber 2. The slidable connections are to give an adjustable coupling. The output circuit is shown also as a concentric transmission line having outer conductor 14 and inner conductor 15. The conductor 14 is a push fit in the piston and may be rotated. The conductor 15 is looped and one end of the loop is connected to 14 so that the loop may be rotated, thus providing an adjustable output coupling.

In the arrangement shown in Figure 3, a hollow disc resonator is used for the output circuit, whilst the input circuit is the same as in Figure 1. The disc resonator is indicated as DR, and forms a capacitative connection with the grid of the valve as does the output conductor 2' of Figure 1. The grid 7 of the valve, as in the case of Figure 1, is mounted on an annular copper disc 11 sealed into the glass envelope, and which projects outside the envelope 9 to cooperate with the flange on the outer conductor 2 of the input circuit to form a capacitive coupling. The second copper disc 16 is also sealed into the glass envelope of the valve and acts as a closure for the outer end thereof. This second disc or outer flat wall of the resonator, which is disposed parallel to the first-mentioned disc, has the anode 8 mounted thereon, and the disc resonator DR is built upon the two discs 11 and 16, one flat wall

of the resonator being capacitively coupled to the copper disc 11.

The resonator is tuned to the working frequency by screwing plugs of metal or dielectric substance into the resonant chamber, or alternatively by making adjustable as, by corrugating the copper disc 16 carrying the anode 8 so that the anode can be moved slightly towards or away from the grid, thus varying the anode-grid capacity which loads the resonator.

The output from the resonator is taken by means of concentric conductors 14, 15, the inner conductor 15 being connected to the outer conductor 14 by a loop to form an inductive coupling with the resonator. The conductor 14 is a push fit in the flat end wall of the resonator so as to be rotatable to form an adjustable output coupling.

The advantages of this system are:

(a) The excellent screening of the output from the input circuit and consequent elimination of positive feedback. The only possible source of feedback is the anode-cathode capacity which can be kept extremely low.

(b) The negative feedback inherent in this circuit ensures complete stability and brings all its other advantages. The existence of this feedback is more evident from the equivalent circuit of Fig. 2. The anode current flows through the input impedance Z_g . The input is represented at e .

There is no impedance common to the output and input circuits.

The power or voltage gain from this system can be shown to be:

$$\frac{\mu + 1}{1 + \frac{(\mu + 1)Z_g + R}{Z_a}}$$

where μ is the amplification factor of the tube and R is the plate impedance and Z_a the output impedance.

It will be observed that the tube must have as large a μ as possible consistent with keeping the plate impedance R small. Z_a must be as large as possible subject to obtaining the necessary band-width, and Z_g must be small although it must be equal to the impedance between cathode and grid of the tube in order that the input line should be properly terminated.

The triode is of special design with small cathode-grid spacing to minimise transmit time effects, and has a very fine grid so that the amplification factor may be as large as possible. With a μ of the order of 100 it should be possible to obtain power amplification of 30 times with a bandwidth of 4 mc./s. at a wavelength of 50 cms.

This amplification arrangement overcomes the difficulties due to instability at ultra high frequencies by:

(i) Completely shielding the output from the input circuit.

(ii) Eliminating impedances common to the output and input circuits.

(iii) Reducing the anode cathode capacity to negligible proportions.

(iv) Taking advantage of the properties of negative feedback.

Whilst particular types of connections have been shown on the input and output sides of the amplifier, both types may be used on either side. Furthermore, the coupling between the input and output transmission line and the respective chambers may be made in any other known manner, 15 for instance by capacitive coupling.

What is claimed is:

An amplifier for ultra high frequency comprising input and output resonator chambers at least one chamber consisting of a concentric 20 conductor line section, said chambers being arranged in concentric alignment with each other and each enclosing a portion of an electron discharge device which comprises at least an anode, a cathode and a control grid, said cathode being electrically connected to the input chamber, said 25 control grid having an annular metallic portion extending beyond the enclosing envelopes of the discharge device and sandwiched between the opposed end walls of said two chambers to form 30 an accessible screen between the input and output circuits, blocking capacities inserted in the grid-cathode path and in the grid-anode path, at least one of said resonator chambers together with said grid and said metallic portion and one 35 of said blocking capacity completely housing the part of the discharge device pertaining to said one chamber, at least one of said chambers comprising a hollow disc resonator, the element of 40 said discharge device which is contained in said disc resonator being connected directly to the outer flat wall thereof, and means for moving said element toward or away from the grid for tuning said resonator.
